UNITED STATES PATENT OFFICE.

ENGELBERT A. STRAUB, OF RODNEY, MICHIGAN.

DESIGN FOR A FRUIT-PICKER.

SPECIFICATION forming part of Design No. 29,549, dated October 25, 1898.

Application filed February 10, 1898. Serial No. 669,863. Term of patent 7 years.

To all whom it may concern:

Be it known that I, ENGELBERT A. STRAUB, a citizen of the United States, residing at Rodney, in the county of Mecosta and State of Michigan, have invented and produced a new and useful Design for a Fruit-Picker, of which the following is a specification.

This invention relates to a new and useful design for a fruit-picker.

The essential feature of my design consists in the circular head provided with an extension or shank and the series of pins projecting from the face of the head and slightly converging toward each other.

The design is clearly illustrated in the accompanying drawing, in which I have shown a perspective view of a fruit-picker constructed in accordance with my design.

Referring to the drawing, A indicates a circular head having a shank B extending therefrom.

C represents circular openings in the shank.

Extending or projecting from the face of the head A are the series of round pins or fingers F, arranged in circular order and converging centrally toward each other, as clearly shown.

Having thus fully described my invention, what I claim as new, and desire to secure by Letters Patent, is—

The design for a fruit-picker herein shown and described.

ENGELBERT A. STRAUB.
